UNITED STATES PATENT OFFICE.

EBER J. HUBBARD, OF BERWYN, ILLINOIS.

BOBBIN.

1,388,951.

Specification of Letters Patent. Patented Aug. 30, 1921.

Application filed February 21, 1919. Serial No. 278,534.

To all whom it may concern:

Be it known that I, EBER J. HUBBARD, a citizen of the United States, and a resident of Berwyn, in the county of Cook and State 5 of Illinois, have invented certain new and useful Improvements in Bobbins, of which the following is a specification.

My invention relates to bobbins, and particularly to so-called mule bobbins for mule 10 shuttles of weaving machines.

These mule bobbins comprise a base part and a shank part, the base part serving to center and hold the bobbin within the shuttle and the shank part supporting the yarn 15 or thread to be fed out during operation of the shuttle. Heretofore these bobbins have been constructed entirely of wood. As the cost of wood has now considerably increased, the cost of manufacturing wooden bobbins 20 is now correspondingly high. Furthermore the wooden bobbins are easily chipped and split, and will readily burn. Another disadvantage is their limited capacity. The shuttle affords only limited space for the 25 bobbin and as a wooden bobbin must have sufficiently thick walls to give the necessary strength, the yarn or thread supporting space is materially limited.

The object of my invention is to overcome 30 the disadvantages of the wooden bobbin by using sheet metal, preferably steel. The base and shank parts of the bobbin being cylindrical, thin sheet steel when bent to form these parts will give great strength. 35 This great strength of the steel over that of wood will of itself permit the diameter of the shank to be materially reduced, and the thinness of the steel wall gives a further reduction of the external diameter, the result 40 being that the thread or yarn capacity is greatly increased over the space available on wooden bobbins. Furthermore the steel bobbin is fireproof, will not chip nor split, and can be more cheaply constructed than 45 the wooden bobbin.

The various features of my invention are clearly shown on the accompanying drawing, in which—

Figure 1 is a side elevational view of a 50 bobbin.

Fig. 2 is a sectional view on plane 2—2 of Fig. 1.

Fig. 3 is a plan view of the base part.

Fig. 4 is a sectional view on plane 4—4 of 55 Fig. 2.

Fig. 5 is a sectional view on plane 5—5 of Fig. 4, and

Fig. 6 is an enlarged sectional view on plane 6—6 of Fig. 1.

The bobbin comprises the base part B and 60 the shank part S. The base part is formed integral of sheet metal preferably by drawing a circular blank of sheet metal.

The base shown is cylindrical, with its top 65 wall 10 slightly arched and provided with the center opening 11. The end of the bobbin is preferably deflected inwardly to form the radial flange 12, which forms a smooth seat for the bobbin and gives a finished appearance. Intermediate its top and base 70 flange the body part has the peripheral groove 13 for receiving the shuttle clamping members (not shown) for holding the bobbin in proper position in the shuttle.

The shank S of the bobbin is formed from a 75 flat blank of sheet metal by rolling around a mandrel. The shank is of circular cross section throughout, but tapers gradually from base to tip. Tongues 14 on one of the edges 80 of the blank engage under the opposite edge when the shank is formed, and these tongues serve to hold the edges in proper alinement and may be spot-welded in place to lock the edges firmly together. In order to 85 strengthen and stiffen the shank as well as to provide barriers or retarder projections for the yarn or thread, annular corrugations or ridges 15 are provided, the shank blank being preferably first corrugated transversely before bending to form the shank. 90

In order to rigidly secure the shank to the body part, tongues 16 are formed at the base end of the shank, which extends through notches 17 cut in the edge surrounding the opening 11 of the base, the tongues 95 after engaging in the slots being deflected over against the inside of the top 10 and preferably spot-welded thereto. The diameter of the opening 11 is preferably equal to the inner diameter of the shank at its base so that when the tongues 16 are secured the shank will be securely locked in 100 abutting engagement against the body part.

I thus produce a very strong, light and 105 efficient bobbin of sheet metal whose capacity greatly exceeds that of the old style wooden bobbin. The annular corrugations on the shank greatly strengthen and stiffen the shank, and at the same time serve to hold the thread or yarn securely on the shank. 110

The body part is also greatly strengthened by its flange 12 and the internal ridge which forms the notch for receiving the clamping devices within the shuttle. When the bobbin is to be rewound it is slipped over a suitable spindle in the same manner as is the wooden bobbin.

As changes and modifications will no doubt be made, I do not desire to be limited except as pointed out in the appended claim.

Having described my invention, I claim as follows:

A bobbin comprising a cylindrical base part stamped integral from sheet metal and having a large opening in its base and a smaller opening in its top wall, a shank formed of a single piece of metal bent into

conical form with its edges intimately abutting along their entire length, tongues extending from one of said edges and the other edge having depressions for receiving said tongues, said tongues being spot-welded to the metal at said depressions whereby said shank becomes a rigid structure, said shank at its lower end abutting on said base part around said upper opening, grooves in the edges of said opening, and tongues extending from the end of said shank through said grooves and deflected outwardly against the under side of the base top and spot-welded thereto.

In witness whereof I hereunto subscribe my name this 18th day of February, A. D. 1919.

EBER J. HUBBARD.
